UNITED STATES PATENT OFFICE.

LOUIS L. DRIGGS, JR., OF NEW ROCHELLE, AND HENRY B. FABER, OF NEW YORK, N. Y.

FIXED AMMUNITION FOR FIREARMS.

Application filed March 20, 1928. Serial No. 263,026.

This invention relates to improvements in fixed ammunition for small arms, and it consists in providing a cartridge case of sufficient size to contain the projectile to be expelled therefrom; and of sufficient strength and rigidity to serve as an auxiliary barrel when the said cartridge case is used with a short barrel small arm, such, for instance, as is illustrated, described and claimed in our co-pending application filed March 20, 1928, Serial #263,024 and entitled Improvements in fire arms. It is the purpose of these inventions to provide for not only low pressures in the piece and for low initial velocity in the projectile, but to expel a projectile of much greater bulk than the size of the small arm would apparently indicate.

For this purpose, a small arm is made with a short barrel having a smooth bore of comparatively large calibre into which the rear end of the cartridge case slides freely, and in which it is automatically held until released by hand.

The cartridge case may be in the form of a single cylinder from end to end, but in order to enable the same to carry a projectile of considerably greater diameter than the calibre of the piece, the part of the cartridge case beyond the barrel of the gun may be enlarged; preferably in the form of a cylinder, concentric with that portion of the cartridge case which projects into the barrel, which may be called the stem of the cartridge case, but of greater diameter than said stem; and this enlarged portion projecting beyond the barrel of the piece serves as an auxiliary barrel to contain the projectile and from which the projectile is expelled when the piece is fired, as will be hereinafter explained.

The invention will be more fully understood after reference to the accompanying drawings, in which one embodiment of the invention is illustrated, and in which like parts are indicated by similar reference symbols throughout the several views.

Figure 1 is a sectional elevation showing the lower half of the cartridge case and contents in a section made by a plane passed through a radius and the longitudinal axis of the cartridge case.

Figure 2 shows a section along the line

2-2 of Figure 1, and looking in the direction of the arrows. 55

Figure 3 shows a section along the line 3-3 of Figure 1, and looking in the direction of the arrows.

Figure 4 shows a section along the line 4-4 of Figure 1, and looking in the direction of the arrows. 60

Figure 5 shows a section along the line 5-5 of Figure 1 and looking in the direction of the arrows.

Figure 6 shows the cartridge case mounted in the small arm with the projectile ejected therefrom, as takes place just after firing the piece. 65

Figure 7 is a diagrammatic view showing the major elements of the projectile after the flare and parachute have been ejected from their container. 70

Figure 8 is a diagram showing the flare and the parachute in the falling position but before the shims containing the parachute have dropped off or the parachute has been distended; and 75

Figure 9 shows the final position of the parachute and the flare with the flare burning from its lower end, and the parachute distended and slowly settling to the ground. 80

A represents the cartridge case, which is shown as having the enlarged cylindrical portion a^1 connected by the flanged annular shoulder a^2 to the cylindrical stem a^3 , which stem slides freely in the barrel of the fire-arm, as described in our application aforesaid. This stem is provided with an annular groove a^4 to engage the spring latch of the fire-arm, and thereby hold the cartridge case in the firing position in the barrel until it is desired to release same. 85

This stem is also provided with the perforation a^5 forming a chamber for the blank cartridge B, which contains a small amount of explosive sufficient to propel the projectile from the cartridge case, but not enough to cause excessive recoil. 90

To limit the shock of recoil, the stem a^3 is provided with an expansion chamber A^6 , 100 in which the powder gases are free to expand before acting on the projectile contained in the loading chamber.

This projectile, which is to be expelled from the loading chamber, may be built up of various component parts suitable for use 105

in carrying signal flares, smoke producing devices, containers for tear gas or the like, or small bombs, or any device which may be conveniently held in the enlarged portion 5 of the cartridge case, and expelled at the proper time, as will be hereinafter described.

However, in the embodiment of the invention herein described, we have shown an illuminating flare adapted to be projected 10 into the air and to be suspended in the air by a parachute, while the flare is burning. Means for igniting the flare and releasing the parachute are also provided in the projectile, as will be hereinafter described in de- 15 tail.

In speaking of the projectile, we mean to refer to all of the parts that are expelled from the cartridge case under the action of the gases of the propelling charge derived 20 from the firing of the small blank cartridge B. This projectile, so defined, comprises a pad of felt or similar material C in front of the base plug E, which may be of wood or other suitable light material. This 25 wooden plug forms one head of the cylinder D slidably mounted in the enlarged portion a of the cartridge case A, which cylinder contains the flare and the parachute, as will be hereinafter described.

30 This cylinder D may be made of aluminum, bakelite, cardboard or other suitable material.

The head E is preferably provided with a flange e to engage the end of the cylinder 35 D. This plug E is chambered as at E^o to contain a suitable expelling charge F of black powder or other explosive, which is ignited a short interval, after the piece has been fired, by a suitable fuse, such as f. 40 We have shown two of such fuses as an extra precaution to assure sufficient action, but one only will suffice. This chamber E^o is closed by a suitable cap e', an ignition charge E' for igniting the flare.

45 In front of the plug E is mounted the cylinder G containing the flare composition, which cylinder is preferably made of cardboard, or other combustible material, so that it will burn away as the flare burns. One 50 end of this cylinder G is closed by the thin cap H made of cardboard, or the like, which may be readily burned or blown out in the operation of the device. An ignition charge h may be used to ignite the flare composi- 55 tion if desired.

The other end of the cylinder G is closed by the flare end cap H', which is securely secured in said end of the cylinder, as by cement or any convenient way. Beyond this 60 end cap, which is preferably made of wood or other light material, a space a⁵ is left in the cartridge case, in which the flare suspension wire L is coiled, as will be hereinafter described. In front of this chamber a⁵ is a 65 gas check or head composed of the felt wad

J and cardboard disk J', which together form one wall of the parachute chamber in which the parachute L is folded up, the opposite wall of the parachute chamber being formed by the wad J², which also may be 70 made of felt or other suitable material.

The parachute is connected by the flare supporting wire to the end cap H' of the flare. The outer end of the cartridge case may be closed in any convenient way, as by 75 means of the cupped head M.

For convenience of assembly, the parachute is normally held in two or more light shims N, which fall away when the flare and parachute are ejected, as will be here- 80 inafter described.

The operation of the device is as follows:

Suppose the cartridge case to be loaded, as shown in Figure 1, and its stem a² inserted in the barrel of the pistol P with the 85 spring latch p engaging the groove a³ of the cartridge case, as described in our application aforesaid. Now, suppose the piece to be cocked and fired. The powder gases from the propelling charge contained in the small 90 blank cartridge B will eject bodily all the parts constituting the projectile, hereinbefore described, and they will carry with them the cap M at the outer end of the cartridge case A.

At the same time the flame from the impelling charge will ignite the fuses f. The projectile, when first ejected from the cartridge case, is shown to the right of Figure 6, where D represents the containing tube 100 or shell, and C represents the felt wad still adhering to the base plug E. As soon as the proper time interval has elapsed, say two or three seconds after the piece has been fired, one or both of the fuses f will light the 105 ejecting charge F, and the cylinder G and its contents will be blown forward, and will drive before it the parts containing the parachute, and the parts of the projectile will then assume the position shown in Figure 7, 110 where the tube D has recoiled in one direction and the flare and parachute have been projected in the opposite direction, the parachute being still held between the shims N and the wads J and J². After being freed 115 from the tube D, the flare will tend to fall by its weight, and the shims will drop off the parachute, as shown in Figure 8, and finally, the parachute will become distended and will lower the flare gradually, as shown 120 in Figure 9. It will be noted that when the ejecting charge F is ignited it will not only blow out the parts of the projectile before it, but it will also ignite the base of the flare, which is opposite the parachute, and when 125 the parachute becomes distended, it will support the flare in such a position that the light from the same will be thrown on the terrain beneath; moreover, the parachute will tend to reflect any rays of light rising 130

vertically in a downward direction, thus casting a shadow upward.

The length of burning of the flare and the illuminating power of the same can be controlled on principles well-known to manufacturers in this art.

After the gun has been fired and the projectile ejected by the propelling charge, as just described, the cartridge case, after serving as an auxiliary barrel, will remain held engaging the short barrel of the piece until released therefrom. This may be accomplished by releasing the spring latch and tilting the piece downward, and allowing the cartridge case to fall out by its own weight, or the empty cartridge case may be withdrawn by hand, and stored away for further use.

Should a misfire occur in the small arm, this may be due to hang fire or defective ammunition, and the loaded cartridge case may be either released and allowed to drop away from the weapon, as when in use on air craft, or after the proper interval for safety, the loaded cartridge case may be removed from the piece by hand, as described hereinbefore.

While we have shown a parachute having a flare as important features of the projectile, it will be obvious that other illuminating or signalling devices may be used or other devices may be carried in the cartridge case, and we do not mean to limit the invention to this particular arrangement.

It will be obvious that various changes might be made in the construction, combination, and arrangement of parts, which could be used without departing from the spirit of our invention, and we do not mean to limit the invention to such details except as particularly pointed out in the claims.

Having thus described our invention, what we claim and desire to secure by Letters Patent of the United States is:—

1. Fixed ammunition for use with firearms, comprising a cartridge case forming an auxiliary barrel for the small arm and provided with a stem adapted to slide freely in the gun barrel with a propelling charge in said stem, the said stem having a chamber for the expansion of the gases from the propelling charge, and said cartridge case having an enlarged loading chamber in front of said stem, with a projectile mounted in said loading chamber, and adapted to be ejected therefrom by the gases from the propelling charge, said projectile comprising a tube closed at its rear slidably mounted in said loading chamber, signalling devices mounted in said tube, and an expelling charge mounted in the base of said tube, with means controlled by the firing of the piece for igniting said expelling charge.

2. Fixed ammunition for use with low power smooth bore fire arms, having a short

barrel of large calibre, said ammunition comprising a cartridge case forming an auxiliary barrel for the small arm and provided with a rearwardly projecting portion adapted to slide freely in the gun barrel with a propelling charge in the rear end of said cartridge case, and having a chamber for the expansion of the gases from the propelling charge, and said cartridge case having a loading chamber in front of said expansion chamber, with a projectile mounted in said loading chamber, and adapted to be ejected therefrom by the gases from the propelling charge, said projectile comprising a tube closed at its rear slidably mounted in said loading chamber, signalling devices mounted in said tube, and an expelling charge mounted in the base of said tube with means controlled by the firing of the small arm for igniting said expelling charge.

3. Fixed ammunition for use with low power smooth bore firearms, having a short barrel of large calibre, with hand controlled means for detachably holding the ammunition in the gun, said ammunition comprising a cartridge case forming an auxiliary barrel for the small arm and provided with a stem adapted to slide freely in the gun barrel with a propelling charge in the rear end of said stem, the said stem having a chamber for the expansion of the gases from the propelling charge, and said cartridge case having an enlarged loading chamber in front of said stem, with a projectile mounted in said loading chamber, and adapted to be ejected therefrom by the gases from the propelling charge, said projectile comprising a tube closed at its rear slidably mounted in said loading chamber, signalling devices mounted in said tube, and an expelling charge mounted in the base of said tube, with means controlled by the firing of the small arm for igniting said expelling charge.

4. Fixed ammunition for use with low power smooth bore fire arms, having a short barrel of large calibre, said ammunition comprising a cartridge case forming an auxiliary barrel for the small arm and provided with a stem adapted to slide freely in the gun barrel with a propelling charge in the rear end of said stem, the said stem having a chamber for the expansion of the gases from the propelling charge, and said cartridge case having an enlarged loading chamber in front of said stem, with a projectile mounted in said loading chamber, and adapted to be ejected therefrom by the gases from the propelling charge, said projectile comprising a tube closed at its rear slidably mounted in said loading chamber, signalling devices mounted in said tube, and an expelling charge mounted in the base of said tube, with means controlled by the firing of the small arm for igniting said expelling charge.

5. Fixed ammunition for use with low power smooth bore firearms, having a short barrel of large calibre with a spring latch normally projecting into said barrel, said ammunition comprising a cartridge case forming an auxiliary barrel for the small arm and provided with a stem adapted to slide freely in the gun barrel with a propelling charge in the rear end of said stem, and an annular groove adapted to engage said latch, the said stem having a chamber for the expansion of the gases from the propelling charge, and said cartridge case having an enlarged loading chamber in front of said stem, with a projectile mounted in said loading chamber, and adapted to be ejected therefrom by the gases from the propelling charge, said projectile comprising a tube closed at its rear slidably mounted in said loading chamber, signalling devices mounted in said tube, and an expelling charge mounted in the base of said tube, with means controlled by the firing of the small arm for igniting said expelling charge.
6. Fixed ammunition for use with firearms, comprising a cartridge case forming an auxiliary barrel for the small arm and provided with a stem adapted to slide freely in the gun barrel, the said stem having a chamber for the expansion of the gases from the propelling charge, and said cartridge case having an enlarged loading chamber in front of said stem, with a projectile mounted in said loading chamber, and adapted to be ejected therefrom by the gases from the propelling charge, said projectile comprising a tube slidably mounted in the loading chamber of the cartridge case, a parachute and a flare mounted in said tube an expelling charge also mounted in said tube for ejecting said parachute and flare and for igniting said flare, and means, controlled by the firing of the small arm, for igniting said expelling charge.
7. Fixed ammunition for use with low power smooth bore firearms, having a short barrel of large calibre, said ammunition comprising a cartridge case forming an auxiliary barrel for the small arm and provided with a rearwardly projecting portion adapted to slide freely in the gun barrel with a propelling charge in the rear end of the cartridge case, and having a chamber for the expansion of the gases from the propelling charge, and said cartridge case having a loading chamber in front of said expansion chamber, with a projectile mounted in said loading chamber, and adapted to be ejected therefrom by the gases from the propelling charge, said projectile comprising a tube slidably mounted in the loading chamber of the cartridge case, a parachute and flare mounted in said tube, an expelling charge also mounted in said tube for ejecting said parachute and flare and for igniting said flare and for igniting said flare, and means, controlled by the firing of the small arm, for igniting said expelling charge.
8. Fixed ammunition for use with low power smooth bore firearms, having a short barrel of large calibre, with hand controlled means for detachably holding the ammunition in the gun, said ammunition comprising a cartridge case forming an auxiliary barrel for the small arm and provided with a stem adapted to slide freely in the gun barrel with a propelling charge in the rear end of said stem, the said stem having a chamber for the expansion of the gases from the propelling charge, and said cartridge case having an enlarged loading chamber in front of said stem, with a projectile mounted in said loading chamber, and adapted to be ejected therefrom by the gases from the propelling charge, said projectile comprising a tube slidably mounted in the loading chamber of the cartridge case, a parachute and flare mounted in said tube, an expelling charge also mounted in said tube for ejecting said parachute and flare and for igniting said flare, and means, controlled by the firing of the small arm, for igniting said expelling charge.
9. Fixed ammunition for use with low power smooth bore firearms, having a short barrel of large calibre, said ammunition comprising a cartridge case forming an auxiliary barrel for the small arm and provided with a stem adapted to slide freely in the gun barrel with a propelling charge in the rear end of said stem, the said stem having a chamber for the expansion of the gases from the propelling charge, and said cartridge case having an enlarged loading chamber in front of said stem, with a projectile mounted in said loading chamber, and adapted to be ejected therefrom by the gases from the propelling charge, said projectile comprising a tube slidably mounted in the loading chamber of the cartridge case, a parachute and flare mounted in said tube, an expelling charge also mounted in said tube for ejecting said parachute and flare and for igniting said flare, and means, controlled by the firing of the small arm, for igniting said expelling charge.
10. Fixed ammunition for use with low power smooth bore fire arms, having a short barrel of large calibre, with a spring latch normally projecting into the gun barrel, said ammunition comprising a cartridge case forming an auxiliary barrel for the small arm and provided with a stem adapted to slide freely in the gun barrel with a propelling charge in the rear end of said stem, and an anular groove adapted to engage said latch, the said stem having a chamber for the expansion of the gases from the propelling charge, and said cartridge case having an enlarged loading chamber in front of said stem, with a projectile mounted in

said loading chamber, and adapted to be ejected therefrom by the gases from the propelling charge, said projectile comprising a tube slidably mounted in the loading chamber of the cartridge case, a parachute and flare mounted in said tube, an expelling charge also mounted in said tube for eject-

ing said parachute and flare and for igniting said flare, and means, controlled by the firing of the small arm, for igniting said expelling charge.
